UNITED STATES PATENT OFFICE

2,495,798

VESSEL FOR STORAGE OF LIQUIDS AT LOW TEMPERATURES

Ivan L. Wissmiller, Chicago, Ill., assignor to Chicago Bridge & Iron Company, a corporation of Illinois

Application July 21, 1948, Serial No. 39,925

6 Claims. (Cl. 220—15)

1

This invention relates to a vessel for storage of liquids at low temperatures, or more particularly for the storage of liquified natural gas.

The storage of liquified natural gas has become increasingly common. The temperature of the liquified material is in the neighborhood of minus 260 degrees, Fahrenheit. At this temperature, normal steels lose their toughness. It is therefore, necessary to utilize a metal in contact with the natural gas liquid which will retain good toughness at the low temperatures involved. Such metals are herein described as "cold-resisting" metals, whereas the normal steel is herein designated as "cold-susceptible" metal. Usually a nickel or nickel-chromium steel or a copper or aluminum alloy is employed as the cold-resisting metal.

All of the cold-resisting metals now known are relatively expensive. Furthermore, the natural gas liquid being markedly below atmospheric temperature, must be thoroughly insulated. For both reasons the storage vessels are commonly made up in the form of a pair of shells, the inner shell being cold-resisting metal and being separated from an outer shell of cold-susceptible metal by a thick layer of insulation.

The inner shell will, of course, expand and contract markedly as it empties and fills, and will move relative to the outer shell with changes in the temperature difference between them. For this reason the problem of supporting the two shells is a difficult one.

The present invention provides a simple means for supporting an inner and outer shell, which are normally spherical in form, independently upon the same piers. This is accomplished by providing a plurality of piers equally distributed around the periphery of the vessel. The outer shell is provided with a generally cylindrical support on each pier. Concentrically within the cylinder is a support for the inner shell. This support includes an upright dithermal (insulating) member having rocker members at its top and bottom, a stop or guide means which permits the dithermal member to move only inwardly from a predetermined outer position on a radial path, and a leg secured to the inner shell and resting upon the upper rocker member of the dithermal support. As the inner shell moves with reference to the outer shell, the dithermal support rocks.

The invention is illustrated in the drawings, in which Fig. 1 is a vertical elevation storage vessel; Fig. 2 is a fragmentary horizontal section; Fig. 3 is a fragmentary section of elevation

2

through one of the supporting elements; and Fig. 4 is a fragmentary horizontal section taken along the line 4—4 in Fig. 3.

The vessel 10 comprises an inner shell 11 of cold-resisting metal, and this shell is here shown as spherical in form. It may also be spheroidal, elliptical, cylindrical, or partially spheroidal, ellipsoidal, or cylindrical; or any other convenient shape. It is best shown in Figs. 3 and 4; the inner shell 11 is provided with a plurality of depending legs 12 of cylindrical form and made of cold-resisting metal which are welded to the shell at uniformly spaced intervals. At least three such legs are provided. The bottom of each leg is closed by a plate 13. The plate 13 rests on a rocker plate 14 which caps dithermal support 15. This support is preferably a block of wood of sufficient length that heat transfer through it is not greatly in excess of heat transfer from the outer to the inner shell at other points. The bottom of the support 15 is provided with a second rocker plate 16 which rests on a plate 17 supported on a concrete pier 18.

The pier likewise forms a support for a cylindrical leg or support 20 for the outer shell 21, which is normally made of cold-susceptible metal. The space between shells 11 and 12 is filled with any suitable insulating material 22.

A dithermal block 23, preferably of wood, is mounted on a bracket 24 carried by the outer shell 25 of the leg 20, and is positioned adjacent to the top of the dithermal support 15. This block 23 is shaped to permit radial movement of the support 15 inwardly from the position of maximum outward movement shown in Fig. 4. An inner stop member may also be provided, if desired, but it has not been found necessary in practice.

In operation, as the inner shell moves inwardly, the dithermal support 15 moves radially inwardly.

The foregoing detailed description has been given for clearness of understanding only, and no unnecessary limitations should be understood therefrom, for some modifications will be obvious to those skilled in the art.

What I claim as new, and desire to secure by Letters Patent, is:

1. A storage vessel for low temperature liquids comprising an inner shell, an outer shell separated therefrom by an insulating space, a plurality of supporting piers, a cylindrical supporting member for the outer shell on each pier, a support for the inner shell within said cylindrical support comprising a depending leg secured to the inner shell, a vertical supporting

member between the leg and the pier and a pair of rocker plates associated with said vertical member whereby said inner shell may move horizontally radially inwardly or outwardly.

2. A vessel as set forth in claim 1, in which means are provided for limiting outward radial movement of the vertical support.

3. A vessel as set forth in claim 1 in which said vertical support is a dithermal material.

4. A vessel as set forth in claim 1 in which the inner shell is of cold-resisting metal and the outer shell is of cold-susceptible metal.

5. A storage vessel comprising a pair of substantially concentric metal shells, a plurality of vessel supports spaced about the periphery of the vessel, a shell support for the outer shell on each vessel support, and a shell support for the inner shell on each vessel support within the first shell support, said supports for the inner shell including a vertical member having rocker plates

at the top and bottom, whereby radial movement of the inner shell may occur by movement of said vertical member on the plate.

6. A storage vessel comprising a pair of substantially concentric metal shells, a plurality of shell supports for the outer shell, a plurality of shell supports for the inner shell, one of said last named shell supports being located within each of the first named shell supports, said supports for the inner shell including a vertical member having rocker plates at the top and bottom whereby radial movement of the inner shell may occur by movement of the said vertical member on the plate, and vessel support means about the periphery of the vessel supporting said inner and outer shell supports.
